UNITED STATES PATENT OFFICE

162,619

PORTABLE COMMODE AND LAVATORY

Floyd A. Blashfield, Naperville, Ill., assignor to American Hospital Supply Corporation, Evanston, Ill., a corporation of Illinois

Application January 13, 1950, Serial No. 7,191

Term of patent 14 years

(Cl. D4—5)

To all whom it may concern:

Be it known that I, Floyd A. Blashfield, a citizen of the United States, residing at Naperville, county of Du Page and State of Illinois, have invented a new, original, and ornamental Design for a Portable Commode and Lavatory, of which the following is a specification, reference being had to the accompanying drawing forming a part thereof, in which:

Figure 1 is a perspective view of a portable commode and lavatory showing my new design; Fig. 2, a perspective view similar to Fig. 1 but showing the other side thereof; Fig. 3, a top plan view; Fig. 4, a side view in elevation; Fig. 5, a front view in elevation; and Fig. 6, a rear view in elevation.

I claim:

The ornamental design for a portable commode and lavatory, as shown.

FLOYD A. BLASHFIELD.
